UNITED STATES PATENT OFFICE.

PETER J. GORDON, OF NEW YORK, N. Y., ASSIGNOR TO THE H. A. CARY CO.,
OF SAME PLACE.

DESIGN FOR SILVERSMITHS' STOCK.

SPECIFICATION forming part of Design No. 34,054, dated February 12, 1901.

Application filed January 19, 1901. Serial No. 43,956. Term of patent 3½ years.

To all whom it may concern:

Be it known that I, PETER J. GORDON, a citizen of the United States, and a resident of the city of New York, borough of Manhattan, 5 in the county and State of New York, have invented and produced a new and original Design for Silversmiths' Stock, of which the following is a full, clear, and exact description.

Reference is to be had to the accompanying drawings, forming a part of this specification, in which—

Figure 1 is a face view of silversmiths' stock, showing my design; and Fig. 2 is a section on 15 the line 2 2 in Fig. 1.

The invention relates to silversmiths' stock used as a border or like ornament for various articles, such as dishes, bowls, and the like.

The design in its entirety consists of a rococo scroll A, from which depend flowers B, 20 resembling fuchsias, all appearing in relief.

The leading feature of the design consists of the rococo scroll and the fuchsia-flowers.

Having thus fully described my invention, I claim as new and desire to secure by Letters 25 Patent—

The design for silversmiths' stock herein shown and described.

In testimony whereof I have signed my name to this specification in the presence of 30 two subscribing witnesses.

PETER J. GORDON.
